BARRELETTE

Ernest H. Benson, Kansas City, Mo.

Application April 27, 1954, Serial No. 30,200

Term of patent 14 years

(Cl. D58—3)

Fig. 1.

Fig. 2.

Fig. 3.

Fig. 4.

To all whom it may concern:

Be it known that I, Ernest H. Benson, a citizen of the United States, residing at Kansas City, State of Missouri, have invented a new, original, and ornamental Design for a Barrelette, of which the following is a specification, reference being had to the accompanying drawing, forming part thereof, in which:

Fig. 1 is a perspective view of a barrellette embodying my new design;

Fig. 2 is a side elevational view of same;

Fig. 3 is a bottom plan view of same; and

Fig. 4 is a top plan view of the same.

I claim:

The ornamental design for a barrelette, substantially as shown.
